[57] CLAIM

The ornamental design for a combined trapeze bar and hand rings, substantially as shown and described.

DESCRIPTION

FIG. 1 is a front elevational view of a combined trapeze bar and hand rings embodying my new design, the rear side being identical;

FIG. 2 is a top plan view thereof;

FIG. 3 is bottom plan view thereof;

FIG. 4 is a side elevational view thereof; and

FIG. 5 is a sectional view taken along line 5—5 of FIG. 1.
